US00D989558S

(12) **United States Design Patent** (10) **Patent No.:** **US D989,558 S**
Wahl (45) **Date of Patent:** **** Jun. 20, 2023**

(54) **BEVERAGE CONTAINER**

- (71) Applicant: **Pacific Market International, LLC**,
Seattle, WA (US)
- (72) Inventor: **Andrew C. F. Wahl**, Seattle, WA (US)
- (73) Assignee: **Pacific Market International, LLC**,
Seattle, WA (US)
- (**) Term: **15 Years**
- (21) Appl. No.: **29/830,974**
- (22) Filed: **Mar. 16, 2022**

(57) **CLAIM**

The ornamental design for a beverage container, as shown
and described.

DESCRIPTION

FIG. 1 is a top perspective view of a beverage container
showing my new design.

FIG. 2 is a bottom perspective view thereof.

FIG. 3 is a front elevational view thereof.

FIG. 4 is a right side elevational view thereof.

FIG. 5 is a left side elevational view thereof.

FIG. 6 is a rear elevational view thereof.

FIG. 7 is a top plan view thereof.

FIG. 8 is a bottom plan view thereof.

FIG. 9 is a top perspective view of a second embodiment
thereof.

FIG. 10 is a bottom perspective view thereof.

FIG. 11 is a front elevational view thereof.

FIG. 12 is a right side elevational view thereof.

FIG. 13 is a left side elevational view thereof.

FIG. 14 is a rear elevational view thereof.

FIG. 15 is a top plan view thereof; and,

FIG. 16 is a bottom plan view thereof.

The broken lines depict portions of the beverage container
that form no part of the claimed design.

1 Claim, 14 Drawing Sheets
